UNITED STATES PATENT OFFICE.

CHARLES S. WACKERMAN, OF BRIDGEPORT, CONNECTICUT.

DESIGN FOR NARROW WOVEN TRIMMING.

Application filed June 11, 1927. Serial No. 22,402. Term of patent $3\frac{1}{2}$ years.

To all whom it may concern:

Be it known that, I CHARLES S. WACKERMAN, a citizen of the United States, residing at Bridgeport, county of Fairfield, State of Connecticut, have invented a new, original, and ornamental Design for Narrow-Woven Trimming, of which the following is a specification, reference being had to the accompanying drawing, forming part thereof.

The figure is a plan view of a piece of narrow woven trimming showing my new design.

I claim:

The ornamental design for narrow woven trimming substantially as shown.

CHARLES S. WACKERMAN.
